UNITED STATES PATENT OFFICE

2,577,078

PENHOLDER CAP WITH INK CONTAINER

Mendel Fried, Phoenix, Ariz.

Application February 10, 1951, Serial No. 210,355

3 Claims. (Cl. 120—7.5)

1

This invention pertains to pen holder caps with ink containers.

One of the objects of my invention is to provide a fountain pen cap which has an ink reservoir in its top with a closable opening from which the pen may be filled, and has a base which will support the cap in a stable manner when the reservoir is opened.

Another object of my invention is to provide a cap for fountain pens or the cases of other pens which are carried in the pocket of the user which has a longitudinal bore in its lower part adapted to fit over the pen grip, a reservoir in its upper part adapted to contain ink, and an exterior including at least one flat surface positioned opposite a radially extending access hole which is closed by a screw cap, or the like, so that the cap may be placed and substantially retained on a level surface where it will support itself with the access hole uppermost and will not tip over.

Another object is to provide a fountain pen cap with an ink reservoir in its upper part which has a radially extending access hole closed by a cap and an outer surface having a flat face opposite said hole forming a base on which the cap may rest in horizontal position.

A still further object is to provide such a cap with an access hole having a neck including a raised rim which is threaded to receive a closing cap and is provided with a clip adapted to secure the cap to the edge of the user's pocket.

Other objects will appear hereinafter.

I attain the foregoing objects by means of the devices and construction illustrated in the accompanying drawings, in which:

Figure 1 is a side elevation of one form of my improved pen cap;

Figure 2, a front elevation thereof;

Figure 3, a bottom end view thereof;

Figure 4, a vertical section taken substantially on lines 4—4, Figure 2, but with the cap placed in a horizontal position and with the drawing made on an enlarged scale; and

Figure 5, a side elevation of the pen cap when opened and used as an ink well.

Similar numerals refer to similar parts in the several views.

In the drawings, 2 indicates the body of a pen cap adapted to fit over and onto the end of a pen barrel indicated by dotted outline 3. When this cap is positioned with its length extending vertically, as shown in Figures 1 and 3, 4 will indicate the lower end. This portion has a cylindrical bore 5 adapted to receive and fit over the

2

end of pen 3. Within the upper portion 6, and separated from bore 5 by a partition 8, is an ink reservoir 10. Access is had to this reservoir through radially extending hole 12 formed in nipple 15 which extends radially outward from the upper side 14 of the cap. Nipple 15 is threaded to receive a closing cap 16.

Opposite upper side 14 is a flat faced base side 18. This may be termed the base side for the reason that when the cap body is removed from the pen, it may be positioned horizontally as shown in Figure 4, and will then rest on any horizontal surface. Base side 18 will then act as a base and will support the cap body with the side 14 uppermost. In its preferred form the cap body has an approximately square, transverse section. The pen cap body may, however, have other prismatic or even semi-cylindrical forms. But in any case it is always necessary, in order to carry out the purposes of my invention, for it to have a flat base side, such as 18.

Nipple 15 is placed as near to the upper end of cap body 2 as possible, and a partial partition 21 along the lower edge of hole 12 may extend into reservoir 10 to form a well, or filling area 22, somewhat separated from the rest of the reservoir. The upper end 6 of the body 2 is smoothly rounded and the lower end somewhat tapered at 24 to join the rim of bore 5.

Closing cap 16 is made of suitable material, integral with clip 26. Its under side is bored and threaded to screw onto nipple 15. A rubber gasket 27 is placed in the upper end of this bore. This provides an effective fluid-tight seal between the cap and nipple 15. When cap 16 is screwed tightly on the nipple the clip will extend downward along side 14 and parallel with the axis of the cap body. When cap 16 is to be unscrewed the lower end of the clip may be swung rotatively as indicated by dotted lines 26a, Figure 2. The clip thus acts as a handle to tighten and loosen the nipple closing cap 16, as well as forming a means for retaining the cap and pen on the edge of a pocket or the like.

In use, the reservoir 10 is filled with ink and the closing cap 16 screwed on nipple 15. The cap body 10 may then be applied to the nib end of a fountain pen 3. The reservoir then provides a convenient supply of ink which may be treated as a reserve, and used to fill or dip the pen should it unexpectedly run dry. If desired, a plain pen holder and steel pen may be substituted for the fountain pen and the reservoir used as an ink well. When the reservoir is to be opened it is removed from the pen and posi-

tioned horizontally and then placed on an approximately level surface, such as the top of table 2a resting on its base side 18.

Thereafter the closing cap 16 is removed and the pen filled or dipped in the well 22.

From the foregoing it will be seen that I have provided a simple portable ink container which will lie flat when opened with little likelihood of spilling, and which may be attached to and made part of a fountain pen or plain pen holder.

I claim:

1. A pen holder cap having a body with an axial bore at its lower end adapted to fit over the nib end of a pen holder, and an ink reservoir in its upper end having a threaded nipple on one side adjacent its upper end opening provided with an access hole opening into said reservoir, a closing cap, including a clip, threaded onto said nipple, and a flat base side formed along the body opposite the side bearing said nipple. 20

2. A pen holder cap having a longitudinally extending body provided with a flat base side extending there along an axial bore formed in its lower end adapted to receive an end of a pen barrel, an ink reservoir formed in its upper end, a threaded nipple extending radially from the upper end of said body opposite said base side having an access bore extending into said reservoir; in combination with a closing cap hav- 25

10

30

ing a radially extending clip adapted to screw on said nipple and provide a fluid-tight seal thereon when said clip extends downward along the outside of said cap body.

3. A pen holder cap having a substantially prismatically shaped body bored at one end to receive and frictionally retain a pen holder, provided with a longitudinally extending flat base side, and an ink reservoir formed in the other end portion, and a threaded nipple extending radially outward from the said body near the outer end of said reservoir and in a direction opposite said base side bored to provide access to said reservoir, in combination with a closing cap adapted to screw onto said nipple and close said bore therein having an integral radially extending clip, adapted to extend along the side of said cap body when said cap is screwed fluid-tight on said nipple.
